UNITED STATES PATENT OFFICE

ASGER ELLERSGAARD, OF CHICAGO, ILLINOIS, ASSIGNOR TO LINK-BELT COMPANY, OF CHICAGO, ILLINOIS, A CORPORATION OF ILLINOIS

EXCAVATING MACHINE

Application filed January 13, 1928. Serial No. 246,428.

My invention relates to improvements in excavating machinery and has for one object to provide a new and improved type of shovel or excavating machine of the crawler supported type wherein the cross sectional area of the machine may be reduced for shipment without entirely dismantling the apparatus to a size which falls within the standard railroad clearance. Another object of my invention is to provide a device wherein the relatively wide crawler treads which must necessarily be used during the operation of the machine may be conveniently and easily removed and there may be substituted for them a relatively narrow crawler tread wide enough to support the load of the machine during shipment. Another object is to provide a supporting mechanism with which there may be interchangeably used wide working treads and narrow shipping treads. Other objects will appear from time to time in the specification and claims.

My invention is illustrated more or less diagrammatically in the accompanying drawings wherein—

Figure 1 is a side elevation;

Figure 2 is an end view with the apparatus rigged for working;

Figure 3 is an end view with the apparatus rigged for shipping;

Figure 4 is a detail side elevation showing the machine in the act of moving from the working track to the shipping track;

Figure 5 is a section along the line 5—5 of Figure 1;

Figure 6 is a section along the line 6—6 of Figure 4.

Like parts are indicated by like characters throughout the several figures.

A is a crawler frame. Projecting from this crawler frame are a series of crawler supporting brackets A¹ terminating in stub axles A². A³ is a transmission housing carried by the frame; projecting from this transmission housing are driving shafts A⁴. Mounted for rotation with the driving shafts A⁴ are driving sprockets A⁵. Mounted for rotation on the stub end axle shafts A² are supporting and idler rollers A⁶ A⁷, there being an idler sprocket A⁷ of relatively smaller diameter

toward the rear end of the machine. A⁸ is a working crawler track adapted to travel along these idler sprockets and supporting rollers A⁶ and A⁷ and the driving sprocket A⁵, this crawler track being continuous.

It will be noted that the brackets A¹ and their stub end shafts A² extend out far enough so that these rollers may engage the central portion of the relatively wide track, this track being as much as thirty-six inches wide, there being one track on either side of the machine. The transmission from the power source and the control of the tracks for stopping, starting or driving, form no part of my invention and are not here illustrated or described.

B is a shipping crawler track, the links of which are much narrower than the links of the track A⁸, perhaps only fourteen or sixteen inches in width. These tracks, there being one on each side of the apparatus are substantially the width only of the supporting rollers. It will be noted that these tracks also are shown as endless, and are preferably so made, though under some conditions it

might be sufficient to have merely a length of shipping track on each side only long enough to carry the vehicle without having the tracks extending up around the upper sides of the rollers. The tracks A⁸ and the tracks B are

made up of separate articulated track link sections. These sections are held together by pins B¹ in the case of the links forming the track A⁸ and by similar pins B² in the case of the links forming the tracks B but in each case the links are of the same length and the articulated portions of the links are such that a link forming the track B may be pinned to a link forming the track A⁸ so that it is possible to disconnect the working track A⁸, take out the upper links, couple to a section of the working track supporting the apparatus a section of shipping track and move the machine by its own power from the working track onto the shipping track. If desired the

shipping track may be laid on a railroad car and anchored and the machine can draw itself into position or if desired a complete shipping track may be substituted for the working track and the machine may be

90

100

maneuvered from place to place on some roads as it is loaded or unloaded on the car. This is especially desirable because under some circumstances the very wide working tracks make the machine somewhat less maneuverable than the narrow shipping tracks and the narrow shipping tracks are sufficient to support the load when working on a firm foundation.

10   Mounted on the frame A is a ring gear C which provides on its side a track C¹, rollers C² travel along this track and support the working platform C³. A pinion C⁴ extends down from the working platform to mesh 15 with the ring gear C and means are provided not here shown within the housing C⁵ on the working platform to operate this pinion to swing the working platform about its pivot point concentric with the ring gear C. A 20 boom of any suitable type C⁶ is pivoted on the working platform and may be raised and lowered or removed as the case may be. For shipping, this boom may be lowered so that it is supported on a separate railroad car 25 adjacent the car carrying the excavating machine itself. The rear end of the working platform C² is provided with a storage pocket C⁷ in which the separate links forming the working track may be stored so that 30 these links when the machine is in operation may be used as counterbalance weights to counterbalance the boom and the load carried by it, thus making it unnecessary to provide any separate counterbalance weights and 35 since the cost of the links is little more than the cost of the counterbalance weights the expense of these links is negligible.

It is standard practice in building large 40 machines such as illustrated in the drawings of this case, to which the present invention is applicable, to have the overall width of the machine as near the standard clearance width of the rolling stock of steam railways as is practicable, in order that the machines may 45 be shipped upon such railways, and yet have sufficient width to furnish a base for safe operation. The chassis or supporting motor frame of the machine illustrated is formed to 50 provide working spaces for the wide crawler tracks A⁸, below the cab or other superstructure parts of the machine, which cannot extend at the sides beyond the clearance allowances that have been referred to. The axles 55 or supports for the sprockets and rollers with which the crawler tracks engage in practice also extend outwardly or laterally as far as clearance allowances permit so that the referred to working spaces beneath the cab or 60 superstructure parts of the machine extend well inside the vertical planes of the rollers A⁹.

It will be obvious that the mechanism 65 shown is applicable to a loading machine, a drag line excavator, a crane, a shovel or

any device which involves a boom or similar element projecting from the working platform for the purpose of lifting loads or excavating or conveying machinery.

While I have shown my invention as applied to an excavating machine or crane and while I have for the purpose of illustration referred to it in terms of such a device manifestly the invention is equally applicable to any device including a working platform, a housing or cap, a supporting mechanism and working machinery on the platform which can be reduced to smaller cross sectional area for shipment or other purposes than the normal cross sectional area of the machine.

I claim:

A crawler vehicle comprising a frame, axles projecting laterally therefrom, a body mounted thereon above the axles and projecting laterally a distance substantially equal to the projection of the axles, relatively wide rollers on the axles, a plurality of crawler chains comprising articulated links, and adapted to be separated at any articulation point, the links of one of said chains being substantially equal to the width of the rollers, the links of the other of said chains extending laterally beyond the rollers on one side beneath the body toward the frame, on the other side away from the body and the frame, each of said chains being separately adapted to form a closed circuit around the axles upon which the vehicle may travel and when disconnected to be connected to the other chain whereby the vehicle may travel from one chain to the other.

Signed at Chicago county of Cook and State of Illinois, this 11th day of January, 1928.
